UNITED STATES PATENT OFFICE.

ROBERT H. HAZELTINE, OF BORDEAUX, FRANCE, ASSIGNOR TO SPECIALTY MACHINE COMPANY, OF NEW YORK, N. Y., A CORPORATION OF NEW YORK.

AUTOMATIC VALVE GRINDER.

Application filed November 11, 1920. Serial No. 423,278.

To all whom it may concern:

Be it known that I, ROBERT H. HAZELTINE, a citizen of the United States, residing in Bordeaux, France, have invented an Improvement in Automatic Valve Grinders, of which the following is a specification.

This invention relates to an apparatus for grinding valves in internal combustion engines and has for its object the provision of an automatic apparatus that will enable a skilled or an unskilled person to grind a valve to obtain a perfect fit.

A selected embodiment of the invention is shown in the accompanying drawings, 15 wherein—

Figure 1 is a sectional view of an automatic valve grinding apparatus;

Figure 2 is a view in elevation of this apparatus;

Figures 3 to 8 inclusive are diagrammatic views of certain parts of the apparatus in various positions, illustrating the operation of the apparatus; and

Figures 9 and 10 are views of a modified form of a positioning foot.

The embodiment of the invention herein shown illustrates an apparatus adjustably positioned on an internal combustion engine above one of the valves and operatively attached to the valve. The operation of this apparatus is substantially automatic and performs the function of oscillating the valve during grinding, and at intervals moves it to a new position on its seat where it is again oscillated. This cycle of operation is continued until the valve has been properly ground to fit the seat. An independent adjustable means for pressing the valve against the seat during grinding is provided within the apparatus and is independent of pressure exerted in holding the apparatus in position on the engine.

Referring to the drawings, the apparatus preferably comprises a frame 1 which is properly positioned over an internal combustion engine 2 by means of adjusting a positioning foot 3 which permits the frame to be raised or lowered in order that a main shaft 4 carried by the frame and contacting with head 5 of the valve may be properly positioned to exert a pressure on the valve. This pressure is obtained in a suitable manner, as by compressing spring 6 held between collar 7 mounted on the shaft, and a washer 8 held in the frame. It will be apparent by

referring to Fig. 1 that the pressure exerted on a gripping handle 9 is transmitted directly to the engine and does not exert a pressure on the valve. When the apparatus is to be employed for grinding valves in a T or L-shaped motor head, a positioning foot 10 illustrated in Figs. 9 and 10 is substituted for foot 3. The main shaft 4 is attached to the valve by any suitable means, as by a screw threaded projection 11, received in a screw threaded recess in the top of the valve, and a reinforcing means, such as collar 12 carried by the shaft, is adapted to be moved against the upper surface of the valve. Should the valve head be provided with holes or slots instead of the screw threaded recesses, any suitable attachments may be held on the projection 11 for engaging such openings.

The oscillating motion is given to the valve by means of a crosshead 13 operated by a suitable handle 14; the crosshead carrying a rack 15 on its lower end for engagement with a gear 16 which preferably surrounds the main shaft 4. The power is transmitted from the gear to the shaft by suitable means such as keys 17 mounted on the main shaft and held in slots 18 formed in the gear. The oscillation of the valve is preferably equal in each direction.

The valve is rotated or repositioned on its seat at definite intervals by an upward and downward movement of the main shaft which allows the keys 17 to be placed in different slots in the gear 16. When the shaft is raised, no rotary power is transmitted thereto as the keys are free of the slots, and as the gear 16 continues to oscillate other slots will align with the keys. A suitable means for providing the vertical movement of shaft 4 is illustrated in the form of a cam 19 carried on, or integral with, a gear wheel 20 driven by pinion 21 which in turn is operated through a counter-shaft by the handle 14. This cam preferably operates in contact with a roller 22 carried by collar 23 mounted on the main shaft and raises the main shaft and consequently the valve. Rotary movement of collar 23 is prevented by its engagement with arm 24 which is firmly held on the frame of the apparatus.

In the operation of the apparatus which is carried on without requiring special attention of the operator, the manner of oscil-

lating the main shaft is readily understood by reference to Figs. 1 and 2 and from the foregoing description. The method of re-positioning the valve on its seat will be 5 more fully appreciated by reference to Figs. 3 to 8 inclusive where diagrammatic representations of the main shaft, keys, and cam are illustrated in different positions of travel. Referring to Figs. 3 and 4, the start 10 of the upward movement of the shaft is illustrated, and in Figs. 5 and 6, the keys are shown as out of contact with the gear 16, and the roller 22 is on the high point of the cam; and, again, in Figs. 7 and 8, 15 the shaft is shown as dropping as roller 22 moves down the back of the cam 19 and the keys then engage other slots in the gear.

The position of the cam, the size thereof, and the ratio of the circumferential 20 diameters of the gear 20, and the pinion 21 may be varied so that the main shaft, and consequently the valve, are capable of being raised and repositioned at different intervals.

25 This invention may be variously embodied and the particular form of the invention shown may be varied within the scope of the subjoined claims.

I claim:

30 1. A valve grinder comprising a frame to be held against a motor, a main shaft held in said frame and adapted to be attached to a valve, a power operated counter-shaft in said frame, a crosshead driven by a crank on said counter-shaft, means for transmitting the oscillating movement of said crosshead to said shaft to move said shaft in equal arcs in each direction, and means for rotating said shaft periodically to change 35 the position of said valve.

40 2. A valve grinder comprising a frame to be held on a motor, a main shaft held in said frame for engaging a valve, a pressure means associated with said shaft for exerting a pressure on said valve and being independent of pressure for holding said

frame on the motor, a crosshead moving in guides and connected to said shaft through a rack and gear for oscillating said main shaft, and means for automatically moving 50 said valve to different positions on its seat at predetermined intervals.

3. A valve grinder comprising a frame to be held against a motor, a shaft carried thereby for positively engaging a valve, a gear associated with said shaft, a crosshead operating in said frame for oscillating said gear, a counter-shaft and crank for transmitting power to said crosshead, a second gear having a cam surface thereon driven 55 by a pinion keyed to said counter-shaft, and a roller associated with said shaft and with said cam for disengaging said shaft from said first gear by the operation of said cam and for engaging them after said first gear 60 has moved a predetermined amount thereby rotating said shaft and said valve to a new position.

4. A valve grinder comprising a frame adjustably positioned on a motor, a main 70 shaft capable of rotary and vertical movement carried by said frame and engaging a valve and being provided with extending keys, a spring associated with said frame and with said shaft to force said valve on 75 to its seat, a gear surrounding said shaft and having slots therein for holding said keys, a crosshead slidable in said frame and having a rack for engaging said gear to give an oscillating movement thereto, a 80 manually operated counter-shaft carrying a crank for engaging said crosshead, a second gear having a cam surface and rotated by a pinion on said counter-shaft, and a roller 85 affixed to said main shaft for engaging said second gear and adapted to be raised by said cam to raise said main shaft.

In testimony whereof, I have signed my name to this specification this 20th day of October, 1920.

ROBERT H. HAZELTINE.
